UNITED STATES PATENT OFFICE.

ZEBOIM CARTTER PATTEN, OF CHATTANOOGA, TENNESSEE.

ALMANAC OR CALENDAR.

SPECIFICATION forming part of Letters Patent No. 431,281, dated July 1, 1890.

Application filed April 22, 1890. Serial No. 348,958. (No model.)

To all whom it may concern:

Be it known that I, ZEBOIM CARTTER PATTEN, of Chattanooga, in the county of Hamilton and State of Tennessee, have invented a 5 new and useful Improvement in Almanacs or Calendars, of which the following is a full, clear, and exact description.

This invention relates to almanacs and weekly, monthly, or yearly calendars to be 10 used in either book form or on independent pieces of card-board, paper, or other material.

My invention consists in a combination or arrangement, with a calendar or almanac, of a 15 code of symbols indicating the phases of the weather or changes in temperature and weather that may be expected on any day or days in any week, month, or year, and of a series of qualifying symbols to be placed in varied relation with the main symbols, the 20 whole to be arranged on either side, center, or top or bottom of any or each page or sheet of the calendar or almanac and in identifying position with the time or date registering portions of the calendar or almanac to which 25 said symbols are designed to apply, substantially as hereinafter described, and pointed out in the claims.

Reference is to be had to the accompanying drawing, forming a part of this specification, 30 which represents a face view of a calendar or almanac sheet or page for a single month, filled up in part with the usual data of days and dates and other general information, and having the code of symbols indicating changes 35 of weather and temperature in juxta or identifying position with the registering portions of the days and dates of the calendar or almanac.

Although the invention is not restricted to 40 any precise character or form of weather symbols, I adopt in a general way the code of signal-service signs or symbols in general use.

A indicates the sheet or page of a calendar or almanac, taking in a full month, b and c 45 being the columns which compose the register of the days of each week and of the dates of the month such days come upon. The main body of the page or sheet may contain sundry information, such as the times of the rising 50 and setting of the sun for different dates,

when the moon sets and its quarterly changes, the heights of the tide for certain localities, and so forth.

On some convenient portion of the page or sheet is a space d, having a forecast of the 55 weather throughout the period of time the page or sheet covers, and which it will be well to consult in connection with the weather symbols, as the same will be found to more fully indicate the kind of weather that may 60 be expected.

Arranged in juxta or proper identifying position with the column or columns of days and dates b c is a space e, having the code of weather symbols upon it, with the different 65 symbols arranged opposite the particular days and dates said symbols are used to indicate the weather for, or such as is likely to occur. In the symbols as shown, or rather the main symbols, the white-flag symbols f 70 indicate clear or fair weather, no rain, at or about the periods opposite which said symbols are placed; the blue-flag symbols g indicate rain or snow at the periods they refer to; the black triangular symbols h indicate a 75 change of temperature at the periods opposite which they are placed, and the cold-wave-flag symbol i denotes a sudden change and much colder weather at the period it refers to. Besides these main symbols are other 80 qualifying symbols consisting of stars k and Maltese crosses s. When these are used, a Maltese-cross symbol on the left of a blue-flag symbol g indicates snow; a star to the right of said main symbol g indicates that 85 rain may be expected on the particular day in the calendar opposite which such symbol is placed; a star to the right of a main triangular symbol h denotes warmer weather; a Maltese cross to the left of said main symbol 90 h denotes colder weather; a star to the right of the cold-wave signal i would indicate rain, and a Maltese cross to the left of said main symbol i would denote sleet or snow at or about the time the symbol refers to. Of 95 course the symbols herein shown and described are arbitrary, and may be changed as desired, so long as they will have like significance.

Having thus described my invention, I 100

claim as new and desire to secure by Letters Patent—

1. The combination, with a calendar or almanac, of a series of symbols indicative of 5 predicated changes in the weather, the same being arranged in juxtaposition or opposite the dates in the calendar they respectively refer to, substantially as specified.

2. The combination, with a calendar or al- 10 manac, of a series of main symbols indicative of predicated changes in the weather, the same

being arranged in juxtaposition or opposite the dates in the calendar they respectively refer to, and a minor or secondary series of qualifying symbols arranged in juxtaposition 15 to the main symbols, essentially as herein set forth.

ZEBOIM CARTTER PATTEN.
